SMOKING PIPE

William M. O'Neal, St. Louis, Mo., assignor of
one-half to Joseph Wrabetz, St. Louis, Mo.

Application February 16, 1933, Serial No. 656,969

4 Claims. (Cl. 131—12)

This invention relates generally to smoking pipes, and more specifically to smoking pipes constructed and arranged so as to provide for sanitary use thereof, the predominant object of the invention being to produce an improved smoking pipe which includes as a part thereof a readily accessible filtering element which prevents nicotine from reaching the mouth of the user of the improved pipe.

10 Another object of the invention is to provide a smoking pipe with means for controlling saliva which may find its way into the improved pipe.

Fig. 1 is an enlarged sectional view of the improved smoking pipe.

15 Fig. 2 is a fragmentary horizontal section taken on line 2—2 of Fig. 1.

In the drawing, wherein is shown for the purpose of illustration, merely, one embodiment of the invention, A designates the improved pipe generally. The pipe A includes a body portion 1 having a stem-receiving portion 2, a hollow stem 3, and a tobacco-receiving bowl 4. The body portion 1 is provided with a cavity 5 into which an extension 6 formed at the base of the bowl 4 is extended, said cavity and said extension being of such relative diameters that tight frictional contact is provided between the side face of the extension and the wall of the cavity, whereby the bowl is firmly secured to the body portion of the pipe. Instead of providing a frictional joint between the extension 6 of the bowl 4 and the wall of the cavity 5, as described, these parts may be provided with screw-threads, if desired, so as to secure the bowl to the body portion of the pipe.

35 The cavity 5 extends downwardly in the body portion 1 of the pipe A, and at its lower end an annular shoulder 7 is provided which separates the cavity 5 from a second cavity 8 that is located below the cavity 5 and is of less diameter than said cavity 5. This second cavity 8 terminates at its lower end in an annular shoulder 9 which separates the cavity 8 from a bottom chamber 10 that preferably is more or less dish-shaped, as illustrated, because of the presence 40 of a curved annular side wall 10'. Associated with the cavity 8 and the bottom chamber 10 is a removable lining element 11 which is so shaped and proportioned as to contact closely with the wall of the cavity 8, the shoulder 9, and the curved side wall and the bottom wall of the chamber 10.

50 Preferably the lining element 10 is formed of metal or other suitable material and in shape resembles a cup in which a horizontal, annular shoulder 12 is formed intermediate of the top and bottom of said cup.

Supported within the portion of the lining element 10 which is disposed in the cavity 8 and resting upon the shoulder 9 of said lining element is a filtering element 13. The filtering element 13 is formed of fiber or any other suitable material, said filtering element preferably being in the form of a disk, as shown most clearly in Fig. 2, and being provided with a centrally located aperture 14. Also, the outer annular face of said filtering element contacts closely with the inner face of the portion of the lining element 10 located above the shoulder 9, so as to isolate the cavity 5 and the chamber 10 from each other.

55 Extended downwardly from the extension 6 of the bowl 4 is a portion 15 which is provided with a lower portion 16 of reduced diameter, a horizontal, annular shoulder 17 being provided at the point where the portions 15 and 16 meet. The portion 16 is extended through the aperture 14 formed centrally through the filtering element 13 and the shoulder 17 contacts with the top face of said filtering element. Also, a smoke passageway 18, which communicates with the cavity in the bowl 4, is formed longitudinally through the portions 15 and 16 and communicates at its lower 20 end with the lower chamber 10. The presence of the portion 15 within the cavity 5 produces within said cavity an annular space 19 which is shown most clearly in Fig. 2.

The stem 3 of the pipe A includes a reduced portion 3' which is extended into and is frictionally engaged by the stem-securing portion 2 of the body portion 1 of the pipe, and formed in the inner end portion of said stem is a recess 20. The recess 20 receives an enlarged end portion 21 30 of an elongated element 22 which extends forwardly from said recess and passes through an opening 23 formed through a portion 1' of the body portion 1 of the pipe. The element 22 includes a shoulder 24 which contacts with the inner end face of the stem 3. Also, the rear portion of the element 22 is provided with a passageway 25 which communicates with the smoke passageway 3a formed through the stem 3, and the forward portion of said element is provided with a trough 26 which communicates with the passageway 25.

45 In the use of the improved pipe, smoke is drawn from the bowl of the pipe downwardly through the smoke passageway 18 and into the lower 50 chamber 10, the smoke then passing through the filtering element 13 into the annular space 19, whereby impurities are removed therefrom. From the space 19 the smoke passes through the opening 23 into the space 27, whence said smoke passes 55

through the passageways 25 and 3^a to the mouth of the user of the pipe. Any saliva which finds its way into the pipe through the stem thereof moves from the smoke passageway 3^a of the stem 3 through the passageway 25 of the element 22 and along the trough 26, said saliva being discharged from said trough onto the top surface of the filtering element 13 by which it is absorbed.

When it is necessary to clean the improved pipe 10 the stem 3 and element 22 are removed and the bowl is displaced from the body portion 1. The filtering element 13 may then be removed and the lining element 11 may also be removed and cleaned or replaced by a new lining element. A new 15 filtering element is then arranged in place, and after the smoke passageway 18 at the base of the bowl is cleaned out by moving the reduced portion of the element 22 through said smoke passageway, the bowl 4, element 22, and stem 3 are reassembled, as shown in Figs. 1 and 2, to produce the 20 complete pipe.

It is apparent from the foregoing that the improved pipe is capable of being maintained in a sanitary condition with very little effort, whereby 25 the pleasure of pipe smoking will be greatly increased.

I claim:

1. A smoking pipe comprising a body portion provided with a chamber, a bowl removably supported by said body portion, a stem associated with said body portion, a filtering element arranged within said body portion in such manner that said chamber is separated thereby from the remainder of the interior of said body portion, 30 said bowl having a portion which is extended through said filtering element through which portion a smoke passageway is formed, said stem being so arranged with respect to said filtering element that smoke is drawn from said bowl 35 through said smoke passageway into said chamber, and through said filtering element to said stem, and a lining element for said chamber, said lining element being provided with a shoulder for supporting said filtering element.
- 45 2. A smoking pipe comprising a body portion provided with a chamber, a bowl removably supported by said body portion, a stem associated with said body portion, a filtering element arranged within said body portion in such manner that said chamber is separated thereby from the remainder of the interior of said body portion, 50 said bowl having a portion which is extended through said filtering element through which portion a smoke passageway is formed, said stem

being so arranged with respect to said filtering element that smoke is drawn from said bowl through said smoke passageway into said chamber, and through said filtering element to said stem, and a lining element for said chamber, said lining element being provided with a shoulder for supporting said filtering element and said lining element being arranged to embrace said filtering element. 5

3. A smoking pipe comprising a body portion 10 provided with an upper cavity and a lower chamber, a bowl removably supported by said body portion, a hollow stem associated with said body portion, a filtering element arranged within said body portion in such manner that said upper 15 cavity and said lower chamber are isolated from each other thereby, said bowl having a portion which is extended through said upper cavity through said filtering element and into said lower chamber, through which portion a smoke passageway 20 is formed, the smoke passageway through said stem being in communication with said upper cavity whereby smoke is drawn from said bowl through the smoke passageway formed through said portion of said bowl into said lower chamber, and through said filtering element to said upper cavity and to said hollow stem, and a lining element for said lower chamber, said lining element being provided with a shoulder which supports said filtering element. 25

4. A smoking pipe comprising a body portion 30 provided with an upper cavity and a lower chamber, a bowl removably supported by said body portion, a hollow stem associated with said body portion, a filtering element arranged within said body portion in such manner that said upper 35 cavity and said lower chamber are isolated from each other thereby, said bowl having a portion which is extended through said upper cavity through said filtering element and into said lower chamber, through which portion a smoke passageway 40 is formed, the smoke passageway through said stem being in communication with said upper cavity whereby smoke is drawn from said bowl through the smoke passageway formed through said portion of said bowl into said lower chamber, and through said filtering element to said upper cavity and to said hollow stem, and a lining element for said lower chamber, said lining element being provided with a shoulder which supports said filtering element and being arranged 45 to embrace said filtering element. 50
